(57) **CLAIM**

The ornamental design for a LED light bar, as shown and described.

DESCRIPTION

FIG. 1 is a perspective view of a LED light bar showing our new design, with the center portion broken away to indicate indeterminate length;

FIG. 2 is a front view of the LED light bar.

FIG. 3 is a rear view of the LED light bar.

FIG. 4 is a left view of the LED light bar.

FIG. 5 is a right view of the LED light bar.

FIG. 6 is a top view of the LED light bar.

FIG. 7 is a bottom view of the LED light bar; and,

FIG. 8 is a perspective view of a second embodiment thereof, wherein the only difference resides in the front lens panel.

1 Claim, 8 Drawing Sheets
